WINDOW AND IMPROVED CONSTRUCTION
THEREFOR

Sallye Hellman, Jamaica, N. Y.

Application September 21, 1944, Serial No. 555,108

2 Claims. (Cl. 98—96)

My invention relates to a new and improved window and to an improved construction therefore. While the improved window is especially suitable for residences and other buildings, the invention is not to be restricted to any particular type of building or structure.

The principal objects of my invention are to provide a new and improved window which will permit a maximum degree of un-obstructed vision and light, not heretofore possible with windows of known construction; and to provide an improved window which possesses none of the draw-backs and discomforts incidental to windows of usual construction.

Another object of my invention is to provide a non-movable window having ventilating means associated therewith, permitting entrance of air to the desired degree, the said ventilating means being operable from the interior of the room.

Still another object of my invention is to provide a window of novel construction and configuration which, while affording maximum vision and light, will prevent rain, snow, etc., from entering the room.

Still another object of my invention is to provide an improved construction for windows which eliminates sliding frames or sashes, and moreover leaves the window entirely free and clear of any obstructing frame work or the like.

Still another object of my invention is to provide a window of novel configuration and construction and which is extremely attractive and ornamental and which will greatly enhance the appearance of the building.

Still another object of my invention is to provide an improved window having a single pane of glass or similar transparent material.

The foregoing and other objects will appear more clearly from the following detailed description, when taken in connection with the accompanying drawings, which illustrate a preferred embodiment of the invention.

In the drawings—

Fig. 1 is a front elevation of the partial exterior of a building wall provided with three of the windows constructed in accordance with the invention.

Fig. 2 is a vertical sectional view on the line 2—2 of Fig. 3.

Fig. 3 is an interior elevational view, shown partially broken away for the convenience of illustration.

Fig. 4 is a sectional view on the line 4—4 of Fig. 2.

Fig. 5 is a sectional view on the line 5—5 of Fig. 2.

Fig. 6 is a sectional view on the line 6—6 of Fig. 4.

Fig. 7 is a sectional view on the line 7—7 of Fig. 4.

Referring to the drawings, the reference letter F represents a window frame comprising the vertical side-pieces or side stiles 10, the upper curved section 11 and the base section 12. Said frame F forms the window opening and said frame can be made of wood, metal or any suitable material. Side stiles 10 and upper section 11 are formed with the continuous groove or channel 13 to receive the top and side edges of the transparent window pane P, thus covering and overhanging the window opening. Groove 13 follows the general configuration of stiles 10 and upper section 11.

As shown in Fig. 2, window pane P consists of a single continuous curved piece of glass or similar transparent material. Said pane P is concavo-convex with the convex face being to the outside thereof, the concavity facing the interior of the room.

Pane P is formed with a downwardly depending bulged-out portion which extends outwardly as the said pane extends downwardly, thus forming a spaced, semi-elliptical shaped opening O 30 between the bottom end of said pane and base section 12 of frame F, or the wall of the building. By reason of such configuration and construction, rain, snow, dust, etc., is prevented from entering the room or building. Moreover, with 35 the convex face of the bulged-out portion of pane P being to the outside of the window, any rain, snow, etc., falling on the outside of the said window will perforce flow off. In addition, dust, etc., will not readily collect on the exterior of the 40 improved window as is the case with the usual flat window panes.

It will be noted that window pane P is more in the nature of an overhanging hood which extends outwardly from frame F, or the wall of 45 the building. The bottom curved edge of said pane P is offset with respect to the top and side edges of said pane.

To prevent injury to the bottom free curved edge of pane P, the same is covered with the U-shaped protective strip or binding 14, which can be secured thereto by any suitable adhesive or the like. Said protective strip can be made of rubber, metal or any other suitable material.

Referring now to the ventilating means and 50 the means for closing opening O (particularly to

Figs. 4 and 5), the reference numeral 15 designates a turnable shaft, the ends of which are loosely mounted in bearings 16 secured to the inner walls of side stiles 10 at the base thereof. Said shaft 15 is parallel to base section 12 of frame F and extends transversely of the window wall opening. Fixedly secured to said shaft 15 and turnable therewith is the bevelled gear G1, said gear being normal to the longitudinal axis of said shaft. Located above shaft 15 is the bevelled gear G which meshes with gear G1, said gear G being parallel to shaft 15 and being connected to the depending shank of crankhandle H. Said crank-handle H and gear G are turnably mounted upon and supported by the stepped bearing member B, the lower horizontal leg of said member B being bolted or otherwise secured to the top wall of base section 12 of frame F. The shank of crank-handle H passes through the upper horizontal leg of said member B. It will be noted that gear G is turnable with crank-handle H and is perpendicular to gear G1, with which latter gear it meshes.

Keyed to shaft 15 and turnable therewith are the spaced pair of brackets 18, each having a ledge 18a which support the semi-elliptical screen S. Said screen S can be secured or connected to ledges 18a in any desired manner. The turning of shaft 15 will cause brackets 18 and screen S to turn therewith. Screen S is of a sufficient size to cover opening O when said screen is brought into the horizontal closed position shown in full lines in Fig. 2. The curved edge of screen S is connected to a stepped marginal member 19, the curved edge of said screen resting upon and being secured to the lower horizontal leg of said member 19. Member 19 can be made of metal, rubber, wood or any other suitable material.

Loosely mounted upon shaft 15 are a pair of arms 17, each of said arms being located adjacent each bracket 18. Each arm 17 is provided with a set-screw 22 whereby each arm can be rigidly secured to shaft 15 if desired. Depending from arms 17 and integral therewith is the semi-elliptical closure member or cover 20, said member 20 being provided with the upstanding peripheral flange 21 along its curved edge. Closure member 20 is located posteriorly to screen S. Said closure member or cover 20 may be made of metal, rubber, wood and the like.

It will be noted that gears G and G1, bearing member B and crank-handle H are all positioned intermediate brackets 18 and arms 17.

The screen S and closure member 20 are manipulated entirely from the inside of the new and improved window in the following manner: Crank-handle H may be turned either in a clock-wise or counter clock-wise direction thus causing gear G to turn therewith. Gear G1 is then caused to turn by meshing gear G, thus turning shaft 15. Brackets 18 (mounted on shaft 15) and screen S connected thereto will then be caused to move through an arc of 90 degrees. Fig. 2 shows (in full lines) screen S brought into the fully horizontal position thus covering opening O. In this position, the top face of the upper horizontal leg of member 19 will abut the bottom face of protective strip 14. In this manner, the improved window is fully screened and protected against the entry of flies, mosquitos and other insects. However, sufficient air is enabled to enter through screen S. Fig. 2

also shows in dotted lines the vertical position screen S will assume when it is moved into parallel relation with the wall of the building.

Normally, closure member 20 is in the inoperative position illustrated in Figs. 1 to 3. That is, it is in a vertical position parallel to the exterior wall of the building and abutting the latter. If it is desired to raise said closure member 20 to a horizontal position and completely close opening O and also cover screen S, set-screws 22 are tightened, thereby locking arms 17 to shaft 15. Crank-handle H is then turned causing shaft 15 and closure member 20 to turn in unison therewith. In this manner, said closure member 20 can be brought into a fully horizontal position completely covering and closing screen S and opening O. In this position, the inner face of flange 21 will abut the outer vertical face of protective strip 14.

It is obvious that by merely turning crank-handle H in a clockwise or counterclockwise direction, screen S and/or closure member or cover 20 can be raised or lowered into any desired position.

It will be noted that the wall of the building acts as a stop to arrest the downward swinging movement of screen S and closure member 20. Likewise, the bottom of window pane P serves as a stop to arrest the upward swinging movement of the said members. It is apparent therefore that the swinging movement of said members is restricted to an arc of approximately 90 degrees.

I have shown a preferred embodiment of my invention, but it is clear that numerous changes and omissions can be made without departing from the spirit thereof. For example, the degree of curvature of window pane P may be varied thus varying the size of opening O. Likewise, the arrangement of the ventilating and closing means may be altered or modified as desired.

I claim:

1. In a window, in combination, a frame forming a window opening, a window pane consisting of a single continuous curved piece of transparent material extending outwardly from said frame and overhanging the same and covering said window opening, said pane having a downwardly extending bulged out portion, the lower end of said pane being spaced from the base of said frame and forming a semi-elliptical ventilating opening therewith, means to control the passage of air through said ventilating opening, said means comprising a shaft turnably supported by said frame, a bevelled first gear secured to said shaft and turnable therewith, said gear being normal to the longitudinal axis of said shaft, a bevelled second gear spaced from said shaft and turnably supported by a stepped bearing member, said second gear being parallel to said shaft and meshing with said first gear, a semi-elliptical closure member secured to and depending from said shaft and turnable therewith, and crank-handle means connected to the second gear to turn said second and first gears and shaft whereby said closure member is swung into a position closing said ventilating opening.

2. A combination such as defined in claim 1 in which a semi-elliptical screen is secured to the shaft and is turnable therewith, said screen being located anterior to the closure member.

SALLYE HELLMAN.
